WITNESS:

UNITED STATES PATENT OFFICE.

JOHN H. RICHARDS, OF POCATELLO, IDAHO.

BALLAST CAR.

Application filed March 26, 1923. Serial No. 627,764.

To all whom it may concern:

Be it known that I, JOHN H. RICHARDS, a citizen of the United States, residing at Pocatello, in the county of Bannock and 5 State of Idaho, have invented new and useful Improvements in Ballast Cars, of which the following is a specification.

This invention relates to dumping cars and aims to provide a car divided longitudinally into two car sections mounted for independent pivotal movement, means being provided whereby said sections can be conveniently dumped with a minimum of effort.

15 In carrying out the invention, I make use of a drum having a chain connected therewith and adapted to be wound about and unwound therefrom to control the movements of the car body sections, with the free 20 ends of said chains having an adjustable connection with the car truck, in a manner to vary the degree of movement of the body sections necessary to offset the center of gravity, which causes said body sections to 25 gravitate to their full dumped positions.

Another object of the invention resides in the provision of a brake mechanism for allowing the car body sections to gradually assume their dumped positions, and means 30 for holding the sections in any given position.

The nature and advantages of the invention will be better understood when the following detailed description is read in connection with the accompanying drawings, the invention residing in the construction, combination, and arrangement of parts as 35 claimed.

In the drawings forming part of this application, like numerals of reference indicate similar parts in the several views, and wherein:

40 Figure 1 is a side elevation of a car constructed in accordance with the present invention.

Figure 2 is an end elevation.

Figure 3 is a sectional view taken on line 3—3 of Figure 1.

Figure 4 is a sectional view taken on line 50 4—4 of Figure 1.

Figure 5 is a similar view taken on line 5—5 of Figure 1.

Figure 6 is a fragmentary view, showing the pivotal connection between the body sections and the truck.

Figure 7 is a sectional view taken at a right angle to Figure 6.

Figure 8 is a fragmentary sectional view of one of the car body sections showing the corner extension and the spaced rollers 60 mounted thereon.

Referring to the drawings in detail, A indicates the truck of the car, while the body is longitudinally divided to provide two identically constructed sections indicated at 65 B and C respectively. The truck includes a plurality of cross sills preferably constructed of metal and of inverted U-shaped formation in cross section clearly indicated at 10 in Figures 1 and 6. These sills have horizontally disposed attaching portions 11 which are secured in any suitable manner to the truck A. Also secured to the sides of the truck for each of said sills is a plate 12 provided with a reinforcing rib 13 and an additional projecting portion 14, which constitutes a core received by the sill 10 to strengthen the latter. These sills are arranged between the spaced flanges 15 arranged vertically on the outer side of each 70 car body section, there being a pair of such flanges for each sill as illustrated in Figure 1. A pivot rod 16, passes through the lower extremities of these flanges, which project below the bottom of the car body, also passing through the cross sill and core above referred to. In this manner, the car body sections B and C are mounted for independent 75 pivotal movement, so that either can be swung outwardly to a dumped position as 80 illustrated in Figure 5.

85 For the purpose of elevating the car body sections to a point which will allow them to gravitate to their dumped positions, I make use of a drum 17 mounted upon the shaft 95 18, which is journaled in a supporting structure indicated generally at D and arranged at one end of the truck A. The shaft 18 supports a wheel 19 over which is trained a chain 20, this chain being also trained over a 100 similar wheel 21 fixed upon a shaft 22 arranged beneath and in parallelism with the shaft 18. A larger wheel 23 is fixed upon the shaft 22, and over which is trained a chain 24, the latter being also passed over a wheel 25 105 fixed upon a shaft 26, which is journaled in the supporting structure D beneath and in parallelism with the shaft 22. The shaft 26 is adapted to be manually rotated by means of a hand wheel or the like 27, and 110

motion is transmitted from this shaft to the shaft 18 by reason of the connection between the shafts as just described. By reason of the construction, shown and described, the 5 shaft 18 may be rotated with a minimum of effort in order to elevate the car body sections. Associated with the drum 17 are chains 28 which are adapted to be wound about and unwound from the drum, depending 10 of course, upon the direction of rotation of the shaft 18. The free end of each of these chains is provided with a snap hook 29 which is adapted to be coupled to the adjacent end of the chains 30 associated with 15 the car body sections. It is of course to be understood that each body section B and C is provided with one of the chains 30, which is arranged to extend across the bottom of the particular section of the car and thence 20 upwardly along one side thereof, being terminally provided with a ring 31 to accommodate the snap hook 29 above referred to. Each chain 30 passes between spaced rollers 32 mounted on a corner extension 33 in a 25 manner clearly illustrated in Figures 5 and 8. The ring 31 normally receives a projection 34 carried by the car body to normally hold the chain in a position shown in Figure 5 at the left hand side of the figure, while 30 the other end of this chain is provided with a snap hook 35 adapted to be interchangeably associated with the spaced eye members 36 supported by the car truck A. The purpose for this adjustable connection will 35 be presently described.

From the structure thus far described, it is manifest that either of the car body sections can be swung upon its pivots to a dumped position by simply connecting one 40 of the chains 28 with the rings 31 of one of the chains 30 associated with said body section. Then by turning the shaft 26 in a manner described, the connecting chains 28 and 30 are wound about the drum, thereby 45 elevating the particular body section to a point where the said section is gravitated to its dumped position. In order to permit the car body to gradually assume this position after the said body has passed beyond the 50 center of gravity, I provide a brake drum 38, which is mounted upon the shaft 26, and connect the free ends of the brake element 39 with a manually operable lever 40, so that by manipulating the lever, the car body 55 will be allowed to gradually assume its dumped position. In order to hold the car body in any desired position, I provide a ratchet wheel 41, which is mounted on the shaft 22, and cooperating with this ratchet 60 wheel are the pawls 42 clearly illustrated in Figures 1 and 2. The degree of elevation necessary to offset the center of gravity, varies in accordance with the particular character of the load contained in the body sections B and C, and in order to facilitate the

movements of the body sections under such conditions, I provide an adjustable connection between the lower ends of the chains 30, and the eye members 36 carried by the truck of the car indicated at A. In Figure 5, I 75 have illustrated the application of this particular feature, wherein it will be noted that with a high load, it is necessary to slightly tilt the body section to the position illustrated by dotted lines in Figure 5, and in 75 which instance, the lower end of the chain 30 is connected to the innermost eye 36. On the contrary however, when the body section contains a low load, it is only necessary to tilt the body to a greater extent in order to offset the center of gravity for the purpose above mentioned, and in this instance, the lower end of the chain 30 is connected to the outermost eye 36 as shown by full lines in 80 Figure 5.

Arranged at the other end of the car, that is the end opposite the supporting structure D, I provide a somewhat similar supporting structure indicated at E, and both of these structures include posts 44 90 against the opposite sides of which the body sections are adapted to rest when the sections are in their normal positions as illustrated in Figure 3. The sections are maintained in this position by means of a substantially U-shaped clamp 45, which embraces the adjacent sides of the car body sections as shown in the same figure, and also by means of a bolt 46 which slides in suitable guides 47 mounted on the supporting structure E. The bolt is provided with an opening to provide a locking pin 48 shown in Figure 1. The shaft 18 is journaled in the adjacent post 44 as shown. 100

To prevent endwise movement of the car 105 body sections, I provide cross bars 49, which are arranged in end to end relation as shown in Figure 3, and pivotally mounted on the adjacent post 44. The normal position of these cross bars is indicated by dotted lines 110 50 in Figure 3, extending across the end of the car body sections and supported in this position by ribs 51, which project from the free ends of said bars and repose upon the upper edge of the car body sections. 115 When it is desired to move either of the said sections to a dumped position, the bar 49 provided for the particular section is elevated, and supported in an elevated position in a manner shown in Figure 3. It will be 120 noted in this connection that I have employed a pair of L-shaped supporting elements 40', each of which is provided with a pivot 41' journaled in a suitable bracket as clearly shown in Figure 2. When the bars 29 are swung upwardly to inactive 125 positions, they contact the adjacent ends of the elements 40', which move upon their pivots to allow the bars 49 to be angularly disposed as shown by dotted lines in Figure 130

3. When thus arranged, the bars 40' are returned to their normal positions engaging the underside of the bars 49 to support them in the positions shown in Figure 3. The 5 supporting structures D and E each include a plate 53, and one of these plates is designed to provide curved edges 54, Figure 4 which project beyond the opposite sides of the drum 17, so that the contents of 10 the car body sections will not in any way interfere with the operation of the drum or the chains associated therewith.

What I claim is:—

1. In a dump car, a truck, car body sections mounted for independent pivotal movement, a drum, chains associated with said drum and adapted to be wound about and unwound therefrom, said chains being connected with said body sections, and 20 means for adjustably connecting the lower ends of the chains with said truck to vary the degree of elevation necessary to offset the center of gravity of each body section, and means for rotating the drum.

25 2. In a dump car, a truck, car body sections mounted for independent pivotal movement, means for elevating said sections to offset the center of gravity and allowing said section to gravitate to a dumped position, a manually operable brake for checking the fall of said section, and means for holding said section in any given position.

3. In a dump car, a truck, car body sections mounted for independent pivotal movement, means for elevating said sections to offset the center of gravity and allow said section to gravitate to a dumped position, said means including a drum, chains associated with said sections and connected 40 with the drum to be wound about or unwound therefrom, means for rotating said drum, means for connecting the lower ends of said chains to different points of the truck for the purpose specified, and manually operable means for controlling the 45 fall of said section as it assumes its dumped position.

4. In a dump car, a truck, car body sections mounted for independent movement, 50 a corner extension projecting from each body section, means for elevating said sections to offset the center of gravity and allow said sections to gravitate to a dumped position, said means including a drum,

chains connected with said drum and adapted to be wound about and unwound therefrom, spaced rollers on each extension, and between which said chains pass, the chains for the respective sections being normally arranged at one side and extended across the bottoms thereof, means for adjustably connecting the lower ends of said chains with said truck for the purpose specified, and means for rotating said drum.

5. In a dump car, a truck including a plurality of cross sills of U-shaped formation in cross section, a core for each sill, car body sections mounted for independent pivotal movement, spaced flanges arranged on each car section and receiving said sills, a pivot for each car section passed through the sills and said flanges, and means for elevating the said sections to offset the center of gravity and allow said sections to gravitate to dumped positions.

6. In a dump car, a truck, car body sections mounted for independent pivotal movement toward and away from each other, means for holding said sections side by side normally, means for preventing endwise movement of said sections, means for elevating said sections to offset the center of gravity and allow the section to gravitate to a dumped position, a manually operable brake for checking the fall of either 85 section, and means for holding either of said sections in any given position.

7. In a dump car, a truck, car body sections mounted for independent pivotal movement, means for elevating said sections to offset the center of gravity and to allow said sections to gravitate to a dumping position, said means including a drum, chains associated with each section, chains associated with said drums and adapted to 90 be connected with the chains of said sections, and further adapted to be wound about and unwound from said drum, means for rotating said drum, means for connecting the lower ends of the first mentioned chains to 100 different points on the truck for the purpose specified, and means for controlling the fall of said sections as it assumes its dumping position.

In testimony whereof I affix my signature.

JOHN H. RICHARDS.
